UNITED STATES PATENT OFFICE.

FREDERICK MITCHELL, OF SALE, AND FRANCIS GUNN, OF GORTON,
NEAR MANCHESTER, ENGLAND.

TOOL OR APPLIANCE FOR USE IN ENABLING THE JOINTS OF LEATHER, CANVAS, AND SIMILAR BELTING TO BE JOINED TOGETHER.

No. 806,556.

Specification of Letters Patent.

Patented Dec. 5, 1905.

Application filed October 16, 1903. Serial No. 177,219.

To all whom it may concern:

Be it known that we, FREDERICK MITCHELL, agent, residing at 55 Washway road, Sale, in the county of Chester, and FRANCIS GUNN, manager, residing at Station Road, Gorton, near Manchester, in the county of Lancaster, England, subjects of the King of Great Britain and Ireland, have invented an Improved Tool or Appliance for Use in Enabling the Joints of Leather, Canvas, and Similar Belting to be Joined Together, of which the following is a specification.

This invention relates to an improved tool or appliance for use in enabling the joints of leather, canvas, and similar belting to be joined together, and is particularly applicable for use in connection with belt-joints formed of a series of separate wire staples of approximately U-shaped character and in which the ends of the staples are bent inwardly at right angles to the body of the staple, so as to form pointed ends, which can be clamped into the material forming the belt, leaving extending from the end of the belt a series of loops, which when the two belt ends are brought together lie alternately between each other and have a central pin passed therethrough, thereby forming a flexible joint.

Our invention is designed with the object of dispensing with the somewhat expensive tools used for clamping the staples and in addition to enable the latter to be more regularly arranged in the belt ends.

Our invention will be fully described with reference to the accompanying drawings, in which—

Figure 1 is a sectional elevation of the appliance designed in accordance with our invention; Fig. 2, plan of same; Fig. 3, sectional elevation showing a double form of the device, and Fig. 4, plan of same.

In carrying out our invention in its simplest form we employ a bed or bracket *a*, which may be of a portable character or secured by means of screws *b* or bolts to a bench or more extended bed *c*. The bracket *a* is made of any suitable width, and at one portion of it we arrange a series of slits or slots *d*, into which the staples *e* in their open form, as indicated, may be separately placed. The slits are so arranged as to hold the staples in vertical planes, with the bottom leg of each resting upon a stepped portion *f*, the ends of

the staples being sufficiently open to allow the end of the belt in which the staples are to be inserted to be passed between the points *e'*, as indicated in Fig. 1. The staples *e* are held in position by two rods or pins *g*, one passing inside the angle formed between the two legs of the staples, while the other one is arranged at the rear of the staples, the former limiting the forward movement of the staples and the latter limiting their backward movement in the slits *d*. These pins are inserted through holes formed in the bracket *a* after the staples have been roughly assembled in position.

To make the joint, the ends of the belt *h* are inserted between the staples, as before described, after which the top legs of the staples are hammered or pressed down or closed together, so that their points *e'* may enter the material composing the belt. While we may completely press home the points *e'* of the staples while they are held in position by the pins *g*, we do not prefer to do so, but rather to partially press them home and afterward withdraw the pins and place the end of the belt in position on the top portion *i* of the bracket *a*, with the looped ends of the staples passing into a further series of slits or slots *j* formed on the top portion of the bracket *a*. In this position the staples can be completely hammered or pressed home. On the two ends of the belts being presented together from opposite directions a central pin may be passed through the staples.

In Figs. 3 and 4 we have indicated a double form of the bracket. (Shown in Figs. 1 and 2.) The construction is exactly the same as already referred to and is intended to enable the opposing ends of the belt-joint to be stapled, brought together, and the jointing-pins inserted without having to turn the belt round. The slits *d* at one end may be placed opposite the divisions *d'* at the other.

We are well aware that prior to the date of our application for patent belt-jointing devices have been in use consisting of a base-plate capable of having hinged and fixed thereto two bars or top plates which can be brought together over a series of shallow grooves in the base-plate, the said top plates being provided on their inner sides with a series of grooves of a vertical character registering with the shallow grooves in the base-

plate and adapted to receive wire staples and a stapling-tool for securing the ends of the belt together, such belt ends being clamped down by the top plates while the stapling operation is being performed. To no such apparatus do we lay claim.

What we claim as our invention, and desire to protect by Letters Patent, is—

1. A tool or appliance for the purposes referred to comprising a bracket formed with a stepped portion integral with the bracket and having a series of slits formed in it adapted to receive jointing-staples and also having a hole formed transversely through the intermediate portions of the bracket between the slits and a pin adapted to be passed through said hole substantially as and for the purposes described.
- 15 2. A tool or appliance for the purposes re-

ferred to comprising a bracket formed with a stepped portion integral with the bracket having a series of slits formed in it adapted to receive jointing-staples also having a hole formed transversely through the intermediate portions of the bracket between the slits, 20 a pin adapted to be passed through said holes, a second hole formed transversely through the intermediate portions referred to and located rearwardly of the first hole and a pin adapted to be passed through said hole substantially as and for the purposes described. 25

In witness whereof we have hereunto set our hands in the presence of two witnesses.

FREDERICK MITCHELL.
FRANCIS GUNN.
